UNITED STATES PATENT OFFICE.

JAMES HAMILTON, OF NEW YORK, N. Y., ASSIGNOR TO FRANCIS L. PRUYN, OF NEW YORK, N. Y.

POWER-HAMMER.

1,122,591.

Specification of Letters Patent. Patented Dec. 29, 1914.

Application filed April 29, 1913. Serial No. 764,397.

To all whom it may concern:

Be it known that I, JAMES HAMILTON, a citizen of the United States, and resident of the borough of Brooklyn, county of Kings, 5 city and State of New York, have invented certain new and useful Improvements in Power-Hammers, of which the following is a specification.

The invention relates to power hammers 10 and particularly to steam or air-actuated hammers for driving pilings.

One of the principal objects of the invention is to provide a hammer frame adapted to carry the operating parts and designed 15 to be suspended in a suitable framework or tower and to be lowered as the pile is driven, the frame being provided with suitable guide-ways which engage corresponding vertical guide-ways in the tower or other sup- 20 port.

Another object of the invention is to provide a reciprocable cylinder carrying the hammer head and to arrange a valve mechanism to be operated by said cylinder, said 25 valve mechanism comprising a slide valve with valve operating levers adapted to be engaged by the cylinder at the ends of its movements in both directions.

Another object of the invention is to provide a very simple, strong and efficient valve mechanism adapted to be operated by the reciprocation of the cylinder.

Other objects and advantages of the invention will be more fully described hereinafter.

In the drawing, Figure 1 is a longitudinal vertical sectional view of the hammer; Fig. 2 a side elevation thereof; Fig. 3 a horizontal sectional view on the line III—III of 40 Fig. 1; Fig. 4 a plan view of the hammer; and Fig. 5 a plan view of the hammer frame with operating parts removed.

Referring to the various parts by numerals, 1 designates the hammer frame which 45 is provided on its side edges with the vertical ribs 2 which form channels or guide-ways for the reception of the guide bars of the usual tower or other support in which this type of hammer is usually mounted. 50 The lower end of the frame is provided with the legs 3 between which is mounted an anvil plate 5. Said plate is preferably formed with the four arms 6 arranged at right angles to each other and fitting between the 55 legs of the frame. This anvil plate is held loosely in position by retaining plates 7 which are bolted to the inner sides of the legs. The upper end of the main frame of the machine is open, as shown in Fig. 5, in order that the cylinder and other operating 60 parts may be readily placed in the frame during the process of assembling the parts of the hammer. Rigidly bolted to the top of the frame is a heavy top or cap 8. Formed integral with this cap is a central depending 65 post 9 which serves as a rigid immovable piston rod. To the lower end of this rod is secured a piston 10. Mounted on this piston and piston rod is a vertically reciprocable cylinder 11. The head 12 of the cylinder is 70 formed with a depending internally threaded flange which is adapted to engage a correspondingly threaded portion of the cylinder. By this means the usual cylinder head bolts are dispensed with. In hammers of 75 this construction the cylinder head must be very rigidly secured in position to withstand the strain occasioned by the reciprocation of the cylinder, and by threading the cylinder head to the body of the cylinder all danger of the cylinder head becoming detached from the cylinder is avoided. To prevent the rotation of the cylinder head on the cylinder a dove-tail locking pin 13 is fitted in the cylinder head and in the cylinder, thereby locking the two parts rigidly together 80 and preventing any independent rotation of the cylinder head. When it is desired to disconnect the head from the cylinder it is only necessary to cut through the locking 85 pin at the joint between the head and the cylinder. When the two parts are detached the sections of the locking pin may be easily removed. The cylinder head is provided with a suitable stuffing box 14; and the 90 lower end of the cylinder is formed with a suitable hammer head 15 which is adapted to contact with the anvil plate 5. The cylinder is formed at its sides with vertical webs or ribs 16 which fit corresponding 95 grooves in the hammer frame, said ribs preventing any rotation of the cylinder in the frame. I employ a pair of ribs on each side of the cylinder in order to accurately hold the cylinder in its proper position and 100 to prevent any rotation or undue lateral oscillation thereof.

The rigid piston rod is provided with longitudinally extending passages 17 and 18, the passage 18 extending from the upper 110

surface of the cap 8 through the piston rod, opening into the cylinder below the piston while the passage 17 extends from the upper surface of the cap to a point close to the piston and opens into the cylinder above the piston, as clearly shown in Fig. 1. The upper surface of the cap 8 constitutes a valve seat and operating on said valve seat is a slide valve 19. This valve is formed with an inlet port 20 and two exhaust cavities 21 and 22. Formed in the valve seat are two exhaust passages 23 and 24. All of these passages are arranged close together so that a very slight movement of the valve will be necessary in the operation of the device. Inclosing the slide valve is a box or chest 25 which forms a suitable valve chamber; and steam is admitted to said chamber through pipe 26.

The valve 19 is provided with a valve rod 27 which extends outwardly through the valve chest or box in both directions. The outer ends of this valve rod are adapted to be engaged by the upper ends of valve operating levers 28 and 29, said levers being pivoted in the main frame at 30. Each valve operating lever is formed at its upper end with a valve rod-engaging head 31 and at its lower end with a cam-engaging head 32, both of said heads being rounded on their inner operative surfaces. These operating levers are mounted in suitable longitudinally extending recesses 33 formed in the main frame so that said levers are protected by said frame. Formed on opposite sides of the cylinder are beveled cams 34 and 35, the cam 34 being formed near the upper end of the cylinder and having a cam surface 34^a inclining inwardly and downwardly, while the cam 35 is near the lower end of the cylinder and is formed with a cam surface 35^a which inclines inwardly and upwardly. The cam 34 is adapted to engage the cam 32 of valve operating lever 29 as the cylinder completes its downward movement; and the cam 35 is adapted to engage the head 32 of lever 28 as the cylinder completes its upward movement. It is manifest, therefore, that as the cylinder completes its movement in one direction it will shift the slide valve to connect the inlet port thereof to the proper supply channel of the piston rod and to connect one of the exhaust cavities to the proper passage to permit of the exhaust from the cylinder. The valve operating levers 28 and 29 are so positioned and proportioned that their upper ends will always be in contact with the ends of the valve rod and the lower ends thereof will be in contact either with the cylinder side or with one of the operating cams.

It is manifest from the foregoing that I produce a very simple, strong and efficient hammer operating means; and that the

valve is positively operated in both directions a fixed distance. It is to be noted that the parts are fixed in their relation to each other and that, therefore, there will be no lost motion or rattling of the parts. It will also be noted that the slide valve will have very little movement and that said movement will be very rapid and practically at the end of the cylinder movement in each direction. By this means the entire pressure of the steam is utilized in the driving blow of the hammer.

In the operation of this hammer the cylinder reciprocates so rapidly and strikes so many blows in quick succession that the piling has practically a continuous downward movement during the driving operation. This is of great advantage, particularly in driving sheet metal piling, for the reason that the pile is driven much more easily if it is kept moving and not permitted to become set. It is essential, therefore, that there should be the least possible amount of lost motion in the valve and that said valve shall respond quickly to the valve operating mechanism. The operating levers form positive means for accurately positioning the valve, and said levers practically form positive stops to prevent the valve being driven beyond its proper operative position, in either direction, by the lever operating cams on the cylinder.

What I claim is:

1. A power hammer comprising a hammer frame, a rigid piston rod extending downwardly through said frame and formed with longitudinally extending passages, a piston on the lower end of said rod, a cylinder adapted to reciprocate on said rod, the passages in said rod opening into the cylinder, one above and the other below the piston, a slide valve at the upper end of the frame, exhaust ports formed in the frame adjacent the upper end of the piston rod passages, said valve controlling the admission to and exhaust from the piston rod passages, a valve rod connected to said valve and extending outwardly therefrom in both directions, valve operating levers pivoted in the frame, the upper ends of said levers engaging the ends of the valve rod, cams formed on the sides of the cylinder near opposite ends thereof and adapted to alternately engage the operating levers as the cylinder reciprocates.

2. A power hammer comprising a hammer frame, a rigid piston rod extending into said frame from the upper end thereof and provided with longitudinally extending passages, cams formed on opposite sides of said cylinder near opposite ends thereof, valve operating levers carried by the frame and adapted to be alternately engaged by the cams on the cylinder, a valve in the upper end of the frame and controlling the ad-

mission and exhaust from the piston rod passages, and means whereby said valve will be alternately moved in opposite directions by the upper ends of the valve operating levers.

3. A power hammer comprising a frame open at its upper end, a cap secured to and closing said open end, a rigid piston rod depending from said cap centrally in the frame and provided with longitudinally extending passages, the upper surface of said cap forming a valve seat, a piston on the lower end of said cap, a reciprocable cylinder receiving said piston and movable on said rod, a slide valve mounted on the valve seat and controlling the admission and exhaust from the piston rod passages, a valve rod connected to said valve and depending outwardly in both directions, valve operating levers mounted in opposite sides of the frame, the upper ends of said levers engaging the ends of the valve rod, oppositely disposed cams on the cylinder near opposite ends thereof and adapted to alternately engage the lower ends of the operating levers as the cylinder reciprocates, a pair of vertical guide ribs formed on the cylinder, corresponding grooves being formed in the frame to receive said ribs, and a hammer head formed on the lower end of the cylinder.

4. A power hammer comprising a hammer frame, a rigid piston rod extending downwardly through said frame and formed with longitudinally extending passages, a piston on the lower end of said rod, a cylinder adapted to reciprocate on said rod, the passages in said rod opening into the cylinder one above and the other below the piston, a valve at the upper end of the frame, exhaust ports being formed in the frame adjacent the upper end of the piston rod passages, said valve controlling the admission to and exhaust from the piston rod passages, valve operating levers pivoted to the frame, means operatively connecting the upper ends of said levers to the valve, cams on the sides of the cylinder near opposite ends thereof and adapted to alternately engage the operating levers as the cylinder reciprocates, whereby the valve will be moved in one direction when the cylinder is at the end of its movement in one direction, said valve being moved in the opposite direction when the cylinder is at the end of its other movement.

In testimony whereof I hereunto affix my signature in the presence of two witnesses.

JAMES HAMILTON.
